Attorney.

UNITED STATES PATENT OFFICE.

ALBERT S. NEWTON, OF PROVIDENCE, RHODE ISLAND.

SANITARY DRINKING-FOUNTAIN.

1,209,874.

Specification of Letters Patent. Patented Dec. 26, 1916.

Application filed June 26, 1916. Serial No. 105,804.

To all whom it may concern:

Be it known that I, ALBERT S. NEWTON, a citizen of the United States, residing at Providence, in the county of Providence and State of Rhode Island, have invented certain new and useful Improvements in Sanitary Drinking-Fountains, of which the following is a specification.

My invention relates to sanitary drinking fountains or bubblers, and more particularly to the discharge devices and adjacent parts thereof.

The essential objects of my invention are to insure a uniform height of drinking stream; to vary or control the direction of the stream; to prevent contact of the drinker's lips with the discharge nozzle; to make it impossible, by manually pressing upon the mouth of the nozzle, to create a radial discharge to a distance from the nozzle whereby water is wasted and bystanders drenched; and to attain these objects in a simple and inexpensive structure, readily assembled and disassembled.

To the above ends essentially my invention consists in such parts and combinations of parts as fall within the scope of the appended claim.

In the accompanying drawings which form a part of this specification, Figure 1 is a side elevation of my nozzle and the adjacent parts thereof including a valve with portions broken away and parts in section as on the line 1—1 of Fig. 2. Fig. 2 is a plan view.

Like reference characters indicate like parts throughout the views.

My device in its approved form is herein shown in conjunction with the usual supply pipe A with its external thread a.

B represents any usual or preferred valve in the pipe.

C is a sleeve or tube provided with an internal thread adapted to engage the thread

a. Integral with the top of the sleeve is a circular plate D provided with an annular series of openings d, and having upon its broad edge, side, or periphery a thread above an annular stop shoulder f. The thread engages a thread g upon the lower portion of a cylindrical shield or wall G. In the present instance an annular series of openings or perforations h are formed near the bottom of the shield.

The nozzle J² extends a comparatively short distance above the plate D and the per-

forations h so as to be comparatively remote from the top edge of the shield G. This prevents access of lips to the nozzle. The threaded connection of the member J² with the member D makes it possible to turn the former to any desired radial position whereby the direction of the drinking stream issuing from the nozzle may be controlled. This capacity is important, since, for instance, it is undesirable that the inclined drinking stream be so directed as to fall on the hand manipulating the valve. The inclination of the nozzle J² is purposed to insure an inclined drinking stream since I have found by experiment that a vertical drinking stream is constantly varying in height due to the weight of the water falling back upon the stream. The height of the stream can never approach uniformity unless the drinking stream be discharged at an incline. Not only does the shield G prevent access of the lips to the nozzle, but if a person should place his finger over the mouth of the nozzle so as to radially deflect the stream the deflected portion would impinge against the shield, and prevent the remote travel of the water. It is impossible, also, by placing the palm over the rim of the member G or otherwise, to fill said member, or accumulate by so doing sufficient force to create a radial discharge exterior of the device, as the water escapes through the openings d and h. It will be understood that satisfactory results are attained with only one series of openings, so that either the openings h or d may be omitted if desired.

The described shield prevents, as has already been suggested, the remote travel of the water if the finger be placed upon the mouth of the nozzle. Even more effective results in this respect have been found to be present when, as shown in Figs. 1 and 2, an auxiliary plate L is fixed in an intermediate portion of the member G in a plane slightly above the upper end of the nozzle. This plate is provided with a slightly eccentric opening m and with a plurality of arcuate peripheral openings or slots n. In practice it is found that a person whose finger is inserted in the opening m of the plate receives most of the discharge in his hand and sleeve. The marginal openings n allow passage of the waste water. In Fig. 1 it will be observed that the nozzle J² has a squared shoulder o particularly adapted to receive a wrench to assist in radially adjust-

ing the nozzle. The threaded connection of the member G with the plate D permits a radial adjustment of the member G relatively to the adjusted position of the nozzle J^2 , so that the opening m may be accommodated to the nozzle in any desired position. 5 I claim:—

In a stationary drinking fountain, a base, a vertical shield rotatably adjustable on said 10 base, a nozzle rotatably adjustable in the base and having an inclined bore, said nozzle

zle being of less height than the shield, and a plate within the shield above the nozzle and having an eccentric opening, the adjustment of the shield accommodating the 15 said opening to the adjusted position of the nozzle to throw the stream outward beyond the periphery of the shield.

In testimony whereof I have affixed my signature.

ALBERT S. NEWTON.
